UNITED STATES PATENT OFFICE.

SIMON ARONSON, OF BROOKLINE, MASSACHUSETTS.

ARTIFICIAL FEATHER.

1,152,137.

Specification of Letters Patent. Patented Aug. 31, 1915.

Application filed June 11, 1914. Serial No. 844,575.

To all whom it may concern:

Be it known that I, SIMON ARONSON, a citizen of the United States, residing at Brookline, county of Norfolk, State of Massachusetts, have invented an Improvement in Artificial Feathers, of which the following description, in connection with the accompanying drawing, is a specification, like characters on the drawing representing like parts.

This invention relates to artificial feathers of that type which are made from the fur of animals and the invention has for its object to provide a novel artificial feather which can be inexpensively made and which will have all the appearance and utility of an ordinary feather.

In order to give a proper understanding of my invention I have illustrated a selected embodiment thereof in the accompanying drawings which will now be described, after which the novel features will be pointed out in the appended claims.

In the drawings, Figure 1 is a perspective view of a feather made in accordance with my invention; Fig. 2 is an enlarged perspective view showing the first step in the process of making the feather; Fig. 3 is a similar view showing the two strips of fur and the quill assembled and in condition to receive the stiffening wire; Fig. 4 is a similar view showing the feather complete. Fig. 5 is a partial rear side view of the feather with a portion of the flesh side of the fur strips covered with fur clippings; Fig. 6 is a similar view of a portion of the feather showing the feather completed.

The body portion of my improved artificial feather is made from two strips of fur of the proper size and shape to constitute the two halves of the feather exclusive of the stem, and the quill portion of the feather is formed from a piece of leather or other suitable material to which the strips of fur are sewed, said quill being constructed to constitute a close imitation of the quill of a real feather and also being provided with means for stiffening the artificial feather and holding it in the desired shape.

The two strips of fur are shown at 1 and 2, respectively, and, as stated above, each is of a length and shape corresponding to half the feather to be made. In the manufacture of the artificial feather the inner edges 4 of these two strips of fur are sewed to the opposite edges of a strip 3 of leather,

cloth or other material which constitutes the imitation quill of the feather, as shown in Fig. 2. After this is done the two inner edges 4 of the strips of fur are brought together thereby giving to the quill member 3 a tubular shape, as shown in Fig. 3, and said edges 4 are then sewed together, as at 10, so as to permanently preserve this shape. When the parts are in this condition the quill member 3 forms a tubular rib extending longitudinally of the feather on the front side thereof and simulating the quill of an ordinary feather. A stiffening member is then inserted into this tubular quill 70 or stem, said member being long enough to project below the lower end of the feather to form the stem end thereof, as shown at 6. The stiffening member may be made of any suitable material, such as wire, whalebone, 75 rattan, wood, etc. I find for practical purposes that wire makes a satisfactory stiffening member.

If preferred, I may apply to the back of the feather a covering strip 7 of rubber, 80 cloth or any other suitable material which covers up the seam where the edges 4 of the fur strips are sewed together. This covering 7 is not essential, however. The lower projecting end 6 of the stiffening wire will 85 preferably be covered with some suitable material to give it the appearance of the quill of a feather, and if desired the covering 7 may be of such a character that it can be used to cover the end 6 of the wire. In 90 such case the covering strip 7 will be long enough so that the lower projecting end thereof can be wound about the portion 6 of the wire to suitably cover the latter, or if desired this portion 6 of the wire may be 95 covered by a separate piece of leather, rubber, tape or some suitable material.

When completed the feather may be dyed to any desired color, or the strips of fur can be dyed before they are sewed together. 100 The quill portion 3 may be of any color which harmonizes with or corresponds to the ultimate color of the manufactured feather.

An artificial feather embodying my invention very closely simulates an ordinary feather and can be used for millinery and other purposes in a manner similar to that in which real feathers are used.

The invention is not confined to a feather 110 of the shape shown in the drawings, as feathers of other shapes and sizes may be

imitated by using one or more strips of fur of the proper shape and properly sewing them together.

The fur from which the feather is made 5 may be curled if desired to imitate more closely the shape and characteristics of a feather. A feather with a curved quill can readily be made by merely cutting the piece 3 to the desired shape.

10 In Figs. 5 and 6 I have shown another embodiment of my invention wherein the flesh side of the fur strips is covered with fur clippings. The advantage of this construction is that the rear side of the feather will have a uniform color. In Fig. 5 I have shown a portion of the rear side of the feather on which the flesh side of the fur strips 1 and 2 is exposed. Instead of using the covering strip 7, as shown in Fig. 4, I 15 have illustrated a construction in Fig. 5 wherein the flesh side of the strips 1 and 2 is covered by fur clippings 11. These are short lengths of hair which have been slipped off from the fur strips and in applying them to the flesh side of said strips I propose first to apply a coating of glue or similar adhesive to said flesh side and then sprinkle or deposit the fur clippings thereon in sufficient body to cover up the skin portion of the fur strips. When these fur clippings are deposited on the skin portions of the fur strips they give to the back side of the feather a uniform color which is desirable. This deposit of fur clippings will 20 when deposited present raw or uneven edges 12 and 13 which are more or less unsightly and in completing the feather these raw edges are covered by some of the hairs of the fur strips. This can conveniently be 25 done by drawing the feather through a ring or holder which will cause the hairs to fold up against the strips of skin, and when this is done before the adhesive is thoroughly dry some of these hairs 14 will adhere to 30

the raw edge, thus covering up the latter, 45 as shown in Fig. 6.

I claim:

1. An artificial feather comprising two strips of fur arranged edge to edge, an imitation quill member of tubular shape secured to the meeting edges of the fur strips, and a stiffening member inclosed in and extending longitudinally of the quill member. 50

2. An artificial feather comprising two strips of fur arranged edge to edge and 55 sewed together, a quill member presenting a tubular form in cross section having its edges sewed to the meeting edges of the fur strips, and a stiffening member inclosed within and extending longitudinally of the 60 quill member.

3. An artificial feather comprising two strips of fur arranged edge to edge and sewed together, an imitation quill member tubular in cross sectional shape covering 65 the meeting edges of the fur strips and secured thereto, and a stiffening member inclosed within and extending longitudinally of the quill member.

4. An artificial feather comprising two 70 strips of fur arranged edge to edge and sewed together; an imitation quill member tubular in cross sectional shape covering the meeting edges of the fur strips and secured thereto, and a stiffening member inclosed 75 within and extending longitudinally of the quill member, said stiffening member projecting below the fur strips, and a covering for the projecting end of the stiffening member. 80

In testimony whereof, I have signed my name to this specification, in the presence of two subscribing witnesses.

SIMON ARONSON.
